UNITED STATES PATENT OFFICE.

FAYETTE GOULD, OF NEW YORK, N. Y.

SPEAKING-TUBE ATTACHMENT.

SPECIFICATION forming part of Letters Patent No. 272,541, dated February 20, 1883.

Application filed November 15, 1882. (Model.)

To all whom it may concern:

Be it known that I, FAYETTE GOULD, of New York city, in the county of New York and State of New York, have invented certain new and useful Improvements in Speaking-Tubes; and I do hereby declare the following to be a full, clear, and exact description of the invention, such as will enable others skilled in the art to which it pertains to make and use it, reference being had to the accompanying drawings, which form part of this specification.

My invention relates to an improvement in speaking-tubes; and it consists, first, in a central chamber in which any desired number of tubes center, and which chamber is provided with a whistle which is common to all of the speaking-tubes connected with the chamber; second, a central receiving-chamber having openings through its sides, so as to communicate with all the tubes which center in this chamber, in combination with a revolving mouth-piece having a bent tube attached thereto, and which can be turned so as to communicate with any one of the tubes; third, in the arrangement and combination of parts, which will be more fully described hereinafter.

Figure 1 is a vertical section taken through the receiving-chamber. Fig. 2 is an inverted view of the top of the chamber. Fig. 3 is a view of the chamber with the cover removed. Fig. 4 is a front view of my invention complete.

A represents the receiving-chamber, in which the ends of all the speaking-tubes B center. This chamber is here shown as being made of an annular shape, though I do not confine myself to this or any other form, for one shape will answer as well as another. In the center of this chamber is made the circular recess C, into which the inner end of the mouth-piece L extends, so as to make connection with the bent tube or pipe M', which is secured to the inner end of the mouth-piece, so as to turn with it, and which pipe M' serves to connect the mouth-piece with any one of the speaking-tubes B. Each one of the speaking-tubes has a side passage, F, leading from it to the central recess, C, so as to make connection with the pipe M' and the mouth-piece. In the end E of each speaking-tube is placed a suitable valve, G, which is connected to a button, H, placed upon the outside of the front of the case. When

a person blows in one of the speaking-tubes the air forces the valve G away from its seat D, formed in the speaking-tube, and then the air escapes around the valve into the chamber A, that surrounds the mouth-piece L, and escapes through the whistle I, which is common to all of the tubes. The air from any one or all of the tubes, as above described, passes freely into the outer chamber, A, and in escaping through the whistle I sounds the alarm. By thus having the ends of all of the tubes center in one chamber and providing a single whistle through the cover of the chamber a separate whistle for each tube is done away with, and the cost of the tubes decreased accordingly.

The revolving mouth-piece L, which is placed in the center of the cover of the case or frame, has attached to its inner end the hollow cylinder M, which fits inside of the circular recess C, for the purpose of cutting off communication with all the tubes but one, and serves to center the short bent tube M', connected with the mouth-piece, in position. Fastened to this mouth-piece, which is held loosely in the cover of the case, so that it can be turned freely around, is the pointer O.

When a signal is given through one of the tubes the button H that was blown outward is first forced inward, and then the mouth-piece is turned until this pointer catches over this button, when the inner end of the bent tube M', connected with the mouth-piece, registers with the passage F of the tube through which the signal was made. The valve G being closed in this tube, all that is spoken from either end of the tube can be distinctly heard, for the sound is confined to this tube alone.

By having a cylinder or flange M fit snugly in the recess C, as here shown, communication can be made with only one tube at a time, for all of the passages F, with the exception of the one with which the bent pipe M' registers, are closed.

Having thus described my invention, I claim—

1. The combination of a number of speaking-tubes, a chamber which is common to all of the tubes, a whistle communicating with said chamber, and a valve for each tube capable of closing the entrance to said chamber, substantially as shown.

2. The combination of the frame having a chamber in its outer end, a series of speaking-tubes, all of which communicate with this chamber, a valve for each tube, and a revolving mouth-piece which may be brought into communication with any one of the tubes, substantially as described.
3. The combination of a series of speaking-tubes, each one of which has a short pipe for connection with the mouth-piece, a suitable receiving-chamber, a valve for each tube, and a revolving mouth-piece capable of connection with either tube, substantially as set forth.
4. The combination of a series of speaking-tubes, a chamber that is common to all of the tubes, a valve for each tube, a central receiving-chamber, and a revolving mouth-piece provided with a pointer, substantially as specified.

In testimony whereof I affix my signature in presence of two witnesses.

FAYETTE GOULD.
